UNITED STATES PATENT OFFICE.

ELMER E. IZER, OF POMONA, CALIFORNIA, ASSIGNOR TO POMONA MANUFACTURING COMPANY, OF POMONA, CALIFORNIA, A CORPORATION OF CALIFORNIA.

PUMP.

1,154,316.

Specification of Letters Patent. Patented Sept. 21, 1915.

Application filed August 19, 1914. Serial No. 857,602.

To all whom it may concern:

Be it known that I, ELMER E. IZER, a citizen of the United States, residing at Pomona, county of Los Angeles, and State of California, have invented certain new and useful Improvements in Pumps, of which the following is a specification.

My invention relates to pumps and more particularly to piston pumps, and the object 10 of the invention is to provide means in such pumps whereby large volumes of fluid may be efficiently lifted through considerable distances without the necessity for frequent shutdowns for adjustments and replacements. Such shutdowns are objectionable in all sorts of pumping and particularly so when used to supply water for domestic purposes. This object is accomplished by a new and useful form of packing retainer 15 and a new and useful valve structure, the valves and packing being the vulnerable points in any pump, and any material improvement therein serving to accomplish the above defined object.

25 The new form of valve structure comprised in my invention provides a valve that is naturally self centering and in which the wear on the seats may be considerable without disturbing this self centering feature. 30 It further provides a structure having large, straight openings through which the fluid passes at a low velocity and with a minimum of deflection. This gives a long lived valve as the wear on such a structure is increased if the fluid has to materially change 35 its direction or if the fluid has to pass through restricted openings at high velocities.

The new form of packing retainer comprised in my invention provides means for independently, positively, and securely gripping each of a plurality of packing members so that the load on each member is independently transmitted to the supporting 40 bucket and so that a partial failure of any one of the packing members will not affect the remainder.

45 A further object of my invention is to make the parts most subject to wear of such a form that they can be readily and cheaply replaced.

Further objects and advantages will be defined hereinafter.

50 Certain parts of a vertical duplex water pump have been selected as a convenient em-

bodiment of my invention, and are described herein and illustrated in the annexed drawing.

In the drawing: Figure 1 is an elevation of a portion of a pump column with the two 60 buckets of a duplex pump shown therein certain of the parts being cut away and shown in section to better illustrate the invention. Fig. 2 is a section on the plane x^2-x^2 of Fig. 1 looking in the direction of 65 the arrows. Fig. 3 is a section on the plane x^3-x^3 of Fig. 1 looking in the direction of the arrows. Fig. 4 is an enlarged vertical axial section of a portion of the packing and its supporting structure. Fig. 5 is an enlarged section of one form of clapper and a portion of its seat. Fig. 6 is a similar view 70 of an alternative form of clapper.

In this embodiment of my invention an upper bucket 10 and a lower bucket 11 move 75 vertically in a pump barrel 12, the lower bucket 11 being rigidly connected to an inside rod 13 which passes through the bucket 10, and the upper bucket 10 being rigidly connected to an outside rod 14 which surrounds the rod 13, the rods 13 and 14 extending upwardly to a suitable pumping head forming no part of this invention and therefore not shown.

The lower bucket 11 consists of body 80 member 15 comprising an outer shell 16 and an inner hub 17, the shell and hub being connected by suitable ribs 18 openings 19 being formed therebetween and extending completely through the body member 15. 85 A valve seat 20 is formed on the top of the hub 17 and a valve seat 21 is formed on the top of the shell 16. A short rod 22 is screwed and pinned in the hub 17 and is connected to the rod 13 by means of a head 23. 90 A clapper 24 is machined to form a tight closure when resting on the seats 20 and 21 and has a hub 26 sliding on the rod 22, the head 23 limiting its upward travel and the seats 20 and 21 its lower travel.

100 The outer shell 16 is exteriorly threaded and has a shoulder 27 formed on its upper end. A series of packing members 28 preferably formed of leather and consisting of a disk shaped portion 29 joined with a cylindrical portion 30, have an inner diameter slightly larger than the outside of the shell 16 over which they slip. A series of rings 31 are threaded to fit the threads on the shell 16 and have a series of concentric pro- 105 110

jections 32 formed on their upper and lower faces, these projections being so located that those on one ring would fit into the depressions between the projections on the next one if they were screwed together. A series of holes 33 are formed on the periphery of the rings 32 which may be engaged by a spanner wrench to turn the rings on the shell 16. The dimensions of the rings 31 and the 10 packing members 28 are such that the projections 32 press into the disk shaped portion 29 of the packing members 28 securely gripping and locking these members in place. Each of the rings 31 is in reality a 15 spanner nut.

The upper bucket 10 is similar to the lower bucket 11 except that the rod 13 passes freely through a tube 34 and is secured therein, this tube being connected through 20 an upper head 35 to the rod 14. A clapper 36 slides on the tube 34, the seats thereon and the bucket structure, including the packing members, being similar to that already described in connection with the bucket 11.

25 The method of operation of the invention when applied to a duplex pump is self evident. The buckets 10 and 11 being alternately actuated first one bucket and then the other takes the weight of the water the 30 clappers 24 and 36 rising and falling as the load shifts.

The novelty and utility of the valve structure is diagrammatically illustrated by Figs. 5 and 6. In Fig. 5 the parts are numbered 35 as in Fig. 1. It will be noted that the section of valve seats 20 and 21 are straight lines $a-a$ and $b-b$ the line $b-b$ intersecting the axis $m-m$ at d , these lines $a-a$ and $b-b$ representing the projections of cones 40 having their apexes on the axis $m-m$. Perpendiculars erected at the center of the seats 20 and 21 on the points e and f intersect at the point o on the axis $m-m$. If a sphere be generated about the point o with 45 a radius $o-e$ the cones in which the valve seats 20 and 21 lie will be tangent thereto along circles described about the axis $m-m$. As the radial lengths of the seats 20 and 21 are small the approximation to a spherical 50 seat is close especially after the valves have worn slightly, but the difficulty of machining such conical seats is considerably less than that met with in machining true spherical ones.

55 The construction as illustrated in Fig. 5 is adopted where the diameter of the pump barrel is large. Where small pump barrels are used the construction shown in Fig. 6 is adopted in which seats 200 and 210 are 60 tangent to concentric spheres formed with radii R and r which have a common center p . Such a valve permits of a large opening and substantial seats and I have used it with good success where space conditions 65 made it necessary.

It will be noted that the clapper 24 slides on a short rod 22 and that the clapper 36 slides on a short tube 34 which may be replaced without replacing the rods 13 and 14, an important feature as the movement of the clappers 24 and 36 causes considerable wear at these points. It will further be noted that each of the packing members 28 is individually secured between two of the rings 31 and the destruction or loss of any 75 packing member in no way affects the security of adjacent packing members, the forces acting on each packing member 28 being directly transmitted to the shell 16 without regard to the other packing members 80 28. This is a much superior construction to those now in common use in which the rings 31 would slide freely on the shell 16 being all clamped in place by a single nut or by suitable bolts and in which the 85 tearing out of a single packing member loosens all the others.

I claim as my invention:

1. In a pump, a valve supporting member having an inner and an outer seat formed 90 thereon, and a clapper adapted to make a tight closure with said seats, said seats being frusto-conical in shape the generating cones thereof being tangent to spheres having the same center.

2. In a pump, a valve supporting member having an inner and an outer seat formed thereon, and a clapper adapted to make a tight closure with said seats, said seats being frusto-conical in shape the apex of each 100 generating cone coinciding with the axis of the valve below the seat.

3. In a pump, a bucket having an inner and outer seat formed thereon and having a fluid passage extending therethrough between said seats, a rod secured in said bucket, a valve slidably mounted on said rod and so shaped as to make a tight closure with said seats, said seats being frusto-conical in shape each of the generating cones 110 thereof having its apex located on the axis of said bucket and below the seat.

4. In a pump, a plurality of buckets movable along a single axis each bucket having an inner and an outer seat formed thereon and a fluid passage extending through the bucket between the seats, a rod for each bucket said rods consisting of concentric tubes each secured rigidly in its bucket, and a clapper for each bucket sliding on the rod of that bucket and adapted to make a tight closure with the seats of that bucket, the seats of each clapper being tangent to spheres having a common center located in the said axis.

5. In a pump, a plurality of buckets movable along a single axis each bucket having an inner and an outer seat formed thereon and a fluid passage extending through the bucket between the seats, a rod for each piston, said rods consisting of concentric tubes 120

each secured rigidly in its bucket, and a clapper for each bucket sliding on the rod of that bucket and adapted to make a tight closure with the seat of that bucket, the seats of each clapper being frusto-conical and tangent to spheres having a common center located in said axis.

In testimony whereof, I have hereunto set my hand at Pomona, California, this 14th day of Aug., 1914.

ELMER E. IZER.
